UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR A COFFIN-HANDLE.

SPECIFICATION forming part of Design No. 21,499, dated April 26, 1892.

Application filed April 1, 1892. Serial No. 427,423. Term of patent 7 years.

To all whom it may concern:

Be it known that I, OLIVER McCARTHY, of Meriden, in the county of New Haven and State of Connecticut, have invented a new Design 5 for Coffin-Handles; and I do hereby declare the following, when taken in connection with accompanying drawing, to be a full, clear, and exact description of the same, and which said drawing constitutes part of this specification 10 and represents a face view.

This invention relates to a design for the handle of coffins, with special reference to the class commonly called "bar-handles;" and the invention consists in the design as hereinabove 15 described and shown in the accompanying illustration.

The body of the handle is of cylindrical shape, the levers represented as springing from an annular band on the cylindrical por-

tion. The ends of the bars terminate in tips 20 springing from an enlarged bead on the ends of the handle and curved longitudinally in concave shape and an ornamented boss on the end of the tips, and between the body of the handle and the boss is the representation 25 of an annular bead, forming a band, as shown in the accompanying illustration.

I claim—

The herein-described design for a coffin-handle, as shown in the accompanying illustration. 3c

In testimony whereof I have signed this specification in the presence of two subscribing witnesses.

OLIVER McCARTHY.
